RETAINING RACK FOR SHELVES

William C. Firth, East Cleveland, Ohio, assignor
to The T-Hold Manufacturing Company, East
Cleveland, Ohio, a corporation of Ohio

Application January 30, 1933, Serial No. 654,130

9 Claims. (Cl. 4—68)

This invention relates as indicated to a retaining rack for shelves, and is intended primarily for use on the covers of closet tanks in bathrooms. Heretofore a great deal of annoyance and inconvenience has been caused by objects, which have been placed on these tank covers, falling onto the floor or into the closet. In the first case a breakage of some kind usually results, and in the latter case frequently an obstruction in the plumbing system ensues which is both annoying and expensive to remove. Very often similar experiences are had by those employing other types of shelves or spaces used as shelves.

This invention has for its chief object, the provision of a means for preventing articles from falling from shelves or the like. Another object is to provide a device of this type which can be attached easily to the shelf on which it is to be used. A further object is to provide a device of this kind that may be secured to a wall and become a shelf by the addition of a bottom either glass or other substantial material. A further object is to provide a device of this character which presents a neat and attractive appearance and one which can be manufactured inexpensively and at rapid rates of production.

With these and other objects in view, this invention, then, consists of the means hereinafter fully described and particularly pointed out in the claims. The annexed drawing and following description set forth in detail certain mechanism embodying the invention, such disclosed means constituting, however, but one of the various mechanical forms in which the principle of the invention may be used.

In the annexed drawing:

Fig. 1 is a plan view of my improved retaining rack as applied to the cover of a closet tank. Fig. 2 is a longitudinal elevation of the rack as shown in Fig. 1. Fig. 3 is another elevational view as indicated at 3—3 of Fig. 2. Fig. 4 is another elevational view of the device only, as indicated at 3—3 of Fig. 2 with the addition of a bottom and shown mounted against a wall by the use of screws.

Referring now to the details of construction by reference characters of which like numerals refer to like parts in the several views, the cover 5 of the closet tank 6 represents the shelf herein employed. The rack shown thereon, which is the subject of this invention, contains the two bars 7 and 8, both of which are bent as indicated at 9 and 10 so that the end portions 11 and 12 are disposed substantially at right angles to the center portions. At the ends 13 and 14 the rods are

reduced in diameter as at 13' and 14' to form a shoulder abutting against the bosses or bulges 16' and are riveted or welded to the anchor plates 15, depressions 16 being provided for the up-set portions caused by riveting so as to present a flat surface for contacting with the wall 17 to which the shelf or cover 5 is attached. As a space is usually provided at 18, or, if not originally provided can be arranged for, the ends 19 of the anchor plates 15 whose thickness is of the order of one thirty second of an inch, have a space into which they may project and thus are held in close contact with the wall. The ends 11 and 12 of bars 7 and 8 to which these plates are attached, as above mentioned, are thus held in a fixed relationship with the wall 17 and shelf or cover 5.

In order to maintain the bars 7 and 8 in parallel relationship with each other, the rods 20 are welded to these bars at intermediate points, usually in the vicinity of the bends 9 and 10. The ends of these rods extend below the lower bar sufficiently to maintain the bars in substantially parallel positions relative the surface of the shelf or cover 5 and with the lower bar a little distance above this shelf or cover. The upper ends of 25 these rods 20 are provided with balls 21 which serve as a decorative feature and in addition may be used as a support for light objects, such as towels, which may be conveniently hung thereon.

After the assembly of the rack has been completed by welding, or by riveting and welding, it is usually plated and polished. The operations ordinarily consist of first polishing the rough metal, plating with copper, then buffing, and again plating with nickel and then with chromium after buffing the nickel. For a less expensive product a simple painting or enameling finish is provided.

Anchor plates 15 are provided with a hole 22 that the device may be attached to a wall by the use of screws or nails and by further supplying 40 the device with a bottom 23 supported by rod 8 it becomes a shelf embodying all the protective features previously set forth.

Numerous modifications may be made in the device described such as increasing or decreasing the number of bars 7 and 8 and in changing the number and form of the rods 20 as well as in the form and method of installation of the anchor plates 15. A bent and formed piece of sheet metal 50 may be employed instead of the bars 7 and 8. Other modes of employing the principle of my invention may be employed instead of the one explained, change being made as regards the mechanism herein disclosed, provided the means stated 55

by any of the following claims or the equivalent of such stated means be employed.

I therefore point out and distinctly claim as my invention:

- 5 1. In a device of the character described, the combination of a plurality of bars bent into U-shape, and relatively long and narrow flat plates extending normally to and secured to the ends of said bars, a substantial portion of said plates extending downwardly beyond the lowermost of said bars.
- 10 2. In a device of the character described, the combination of a plurality of bars bent into U-shape, relatively long and narrow flat plates extending normally to and secured to the ends of said bars, and vertical reinforcing bars perpendicular to and secured to said bars, a substantial portion of said plates extending downwardly beyond the lowermost of said bars.
- 15 3. In a device of the character described, the combination of a plurality of parallel bars bent into U-shape, and relatively long and narrow flat plates secured to and extending normally to the ends of said bars, a substantial portion of said plates extending downwardly beyond the lowermost of said bars.
- 20 4. In a device of the character described, the combination of a plurality of parallel bars bent into U-shape, relatively long and narrow flat plates secured to and extending normally to the ends of said bars, a substantial portion of said plates extending downwardly beyond the lowermost of said bars and vertical reinforcing bars perpendicular to and secured to said parallel bars.
- 25 5. In a device of the character described, the combination of a plurality of parallel bars bent into U-shape, relatively long and narrow flat plates secured to and extending normally to the ends of said bars, a substantial portion of said plates extending downwardly beyond the lowermost of said bars and a plurality of vertical projecting bars ex-

tending downwardly from and perpendicular to the lowermost of said parallel bars.

6. A rack for a toilet closet tank, comprising the combination of a plurality of vertically parallel spaced bars bordering and conforming substantially to the outer marginal contour of the top of said tank, and flat tongue-like portions extending from the ends of said bars, said tongue-like portions extending downwardly beyond the lowermost of said bars adapted to be inserted behind said tank and to retain said bars in position above said tank.

7. A rack for a toilet closet tank, comprising the combination of a plurality of spaced bars parallel to and conforming substantially to the outer marginal contour of the top of said tank, and flat tongue-like plates secured to the ends of said bars, said plates having a downwardly extending portion adapted to be inserted behind said tank and to retain said bars in position above said tank.

8. A rack for a toilet closet tank, comprising the combination of a plurality of spaced bars parallel to and conforming substantially to the outer marginal contour of the top of said tank, flat tongue-like plates secured to the ends of said bars, said plates extending downwardly beyond the lowermost of said bars adapted to be inserted behind said tank and to retain said bars in position above said tank, and vertical reinforcing bars perpendicular to and secured to said parallel bars, the ends of said reinforcing bars extending above and below said parallel bars.

9. A rack for a toilet closet tank, comprising a guard railing conforming to the outer marginal contour of the top of said tank and positioned thereabove, and flat tongue-like plates secured to the ends of said railing, said plates having a downwardly extending portion adapted to be inserted behind said tank and to retain said railing in position above said tank.

WILLIAM C. FIRTH.
